UNITED STATES PATENT OFFICE

HOWARD G. MCILVRIED AND KLINE B. WEST, OF GARY, INDIANA, ASSIGNEES TO
AMERICAN SHEET AND TIN PLATE COMPANY, A CORPORATION OF NEW JERSEY

FURNACE DOOR AND CONVEYER CONTROL

Application filed September 9, 1931. Serial No. 561,976.

This invention relates to a door and conveyor control for a continuous heating furnace, one of the objects of the invention being to provide a means whereby, when the operator of the rolling mill opens the door of the furnace, a work unit will be automatically passed through the door and the door will then close. Other objects may later become apparent.

In the drawings:

Figure 1 is a schematic representation of one form of the invention.

Figure 2 is a diagrammatic representation of one method of electrically interconnecting the parts shown in Figure 1.

Having reference to these drawings, there is shown a continuous heating furnace 2 having an interior work conveyor 3 and an exterior work conveyor 4, these two conveyors being interconnected by a drive 5 to be synchronously driven by an electric motor 6. A vertically slideable door 7 is positioned between these conveyors to close the discharge opening in the furnace.

In this instance the work carried through the furnace consists of packs of metal plates 8, it being necessary to withdraw these units from the furnace through the door 7 for working by the rolls 9. To stop the work units 8 proximate the door 7 so that they will be ready for withdrawal from the furnace without the necessity of moving the conveyor 3 to any great extent, a finger member 10 fixed to a shaft 12 which carries a cam 13 is positioned in the furnace 2 at this door. This cam trips a limit switch 14 which is connected in circuit with the motor 6 for stopping the same. When the conveyor 3 is operated to carry the work units 8 through the furnace these units engage the finger member 10 so that the switch 14 is operated and the motor 6 stopped, the units 8 thereby being each successively stopped in position for immediate delivery through the door 7 when the motor 6 is restarted.

A foot switch 15 is located near the rolls 9 and is connected to start a motor 16 geared to a shaft 17. This shaft 17 carries a lever member 18 which is connected to the sliding

door 7 so as to raise the same. This shaft also carries a pair of cams 19 and 20, cam 19 being arranged to simultaneously operate a pair of limit switches 21 and 22. Limit switch 21 is connected with the motor 16 so as to stop it when the door 7 is completely opened, and the switch 22 is connected so as to start the motor 6.

In order to move the finger member 10 out of the path of the work units 8 a solenoid 23 is levered to the shaft 12 and connected to the switch 22 for energization. When the motor 6 is started a work unit 8 is delivered through the door 7 and onto the exterior work conveyor 4, a bar 25 being arranged in its path to be depressed thereby. This bar simultaneously operates limit switches 26 and 27, the limit switch 26 being connected to deenergize the solenoid 23 so that the finger member 10 returns to its original position and the motor 6 is stopped. The limit switch 26 is also connected so as to operate the motor 16 in the reverse direction to close the door 7, the limit switch 27 being then operated by the cam 20 to stop this motor.

The limit switch 27 is connected to the motor 6 to prevent its momentary stoppage during the time it takes the finger member 10 to return to its original position.

One method of interconnecting the parts so as to accomplish the just described functions is as follows:

Direct current lines 28 and 29 are connected by a switch 30 to the motor 6. The line 28 is connected through a relay 31 to the field 32 of the motor 6, a shunt field 33 being arranged between it and the line 29, the motor 6 being dynamically braked by a resistance 34 shunted across its armature through a relay 35. The furnace is started by closing a switch 36 which is connected by means of a line 37 to the line 29 and through the operating coil of a relay 38 to a line 39 leading to the line 28. The relay 38, being thus energized, closes the circuit from the line 29 through the finger operated switch 14 and the operating coils of the relays 31 and 35 to the line 28. The relay 31 closes the circuit to the motor 6 and the relay 35 opens the dynamic braking cir-

cuit so that the motor 6 starts and drives the furnace conveyers.

It is to be understood that the work units are to be placed on the interior conveyer of the furnace at its rear end and advance through the furnace towards the door 7. During this advance they each strike the finger member 10 so as to open the switch 14 and thus deenergize relays 31 and 35, so that the driving current to the motor 6 is cut off and the dynamic circuit is again closed. The interior conveyer is thus stopped with a work unit proximate the door 7 and ready for immediate delivery. When the operator of the rolls 9 desires a work unit for working he uses the foot operated switch 15 to close the circuit to the coil of the double contact relay 40 to the line 28. It also energizes the relay 41 which by-passes the current thereabout so that when the operator releases his foot this circuit will be maintained.

The door lifting motor 16 is energized, through alternating current lines 42, through a pair of relays 43 and 44 which are arranged in circuit therewith for reversing the direction of the current through the motor 16 by operation of relay 40. In this present instance, the right-hand contact of relay 40 is closed so that this motor is operated to raise the door 7. When the door 7 is completely raised the cam 19, carried by the operating shaft 17, operates the limit switches 21 and 22. The switch 21 is thus opened so as to open the circuit to the relay 43 so that the circuit to the motor 16 is broken and it stops.

The limit switch 22 is closed by the door in its present position and energizes the relay 45 so that its left-hand contact closes the circuit from the line 29 through the solenoid 23 to line 28, thus moving the finger 10 out of the path of work units carried by the conveyer 3. Its right-hand contact simultaneously closes the circuit to the relays 31 and 35 so that the motor 6 is again operated to drive the conveyer in the manner first mentioned. As the conveyer was stopped with a work unit proximate the door 7 it follows that this unit is immediately deposited on the exterior conveyer where it depresses the bar 25 so as to operate the limit switches 26 and 27 together.

The switch 26 is connected so as to be opened at this moment, thus deenergizing relays 40 and 41, the right-hand contact of the relay 40 being broken thereby and the left contact closing the circuit to the relay 44 which, in turn, closes the reversing circuit to the motor 16 so that this motor closes the door 7. When the relay 41 is deenergized it breaks the circuit to the relay 45 which deenergizes the solenoid 23 and allows the finger member 10 to swing back into the path of the work units carried by the conveyer 3. The cam operated switch 46 is opened by the closing

of the door 7 and deenergizes switch 44, stopping the motor 16.

During the time it takes the finger member 10 to swing back into a position where the contact 14 will complete the circuit to the relays 31 and 35 there will be an open circuit, the latter two relays being deenergized during this interval so that the motor 6 is stopped and dynamically braked. The switch 27 operated by the bar 25 avoids this momentary stopping by completing the circuit during this interval.

By the use of this invention it is possible for the operator of the rolls 9 to withdraw a unit of work from the furnace 2 very quickly, there being no danger of the door 7 remaining open and allowing loss of heat from this furnace as is now quite customary.

These operations are all automatic and the parts needed may be made of a simplified construction and sufficiently large to withstand the intense heat to which they are exposed. The circuit illustrated may, of course, be varied at will and it is to be understood that a specific form of the invention has been shown in accordance with the patent statutes and not with the intention of limiting the scope of the invention exactly thereto, except as will be defined by the appended claims.

We claim:

1. In combination with a continuous heating furnace having a discharge opening closed by a door, means for moving work through said furnace, means arranged in the path of work moved by said first named means and adjacent said opening for stopping the movement of work through said furnace, means for moving said door and means for moving said second named means out of the path of work units upon movement of said door.

2. In combination with a continuous heating furnace having a discharge opening closed by a door and with one or more conveyers for moving work therethrough and out through this opening, a movable member arranged in said furnace adjacent said opening and in the path of work moved by said conveyers, means operable by movement of said member for stopping said conveyers, means for opening said door and means operable by the movement of said door for starting said conveyers and moving said member out of the path of work moved by said conveyer.

3. In combination with a continuous heating furnace having a discharge opening closed by a door and with one or more conveyers for moving work therethrough and out through this opening, a movable member arranged in said furnace adjacent said opening and in the path of work moved by said conveyers, means operable by movement of said member for stopping said conveyers, means for opening said door, means operable by the movement of said door for starting said conveyers and for

moving said member out of the path of work moved by said conveyers, and means operable by the discharge of work through said opening for closing said door and returning said member to its original position.

4. In combination with a continuous heating furnace having a discharge opening closed by a door and with one or more conveyers for moving work therethrough and out through this opening, a movable member arranged in said furnace adjacent said opening and in the path of the work moved by said conveyers, means operable by movement of said member by said work for stopping said conveyers, means for opening said door, means operable by the movement of said door for starting said conveyers, and means operable by work discharged through said opening for closing said door.

20 In testimony whereof, we have hereunto set our hands.

HOWARD G. McILVRIED.
KLINE B. WEST.
